UNITED STATES PATENT OFFICE.

URBAN S. ALSRUHE, OF TOWSON, MARYLAND.

PLAYING-CARDS.

1,104,724.

Specification of Letters Patent. Patented July 21, 1914.

Application filed September 11, 1913. Serial No. 789,300.

To all whom it may concern:

Be it known that I, URBAN S. ALSRUHE, a citizen of the United States, residing at Towson, in the county of Baltimore and 5 State of Maryland, have invented an Improvement in Playing-Cards, of which the following is a full and complete specification.

The principal object of my invention is to provide a peculiar form of playing card 10 or cards to be employed in the playing of games intended primarily for the amusement and education of children, providing in the present instance a simple and entertaining medium by which they may be easily 15 and quickly taught orthography, and the addition and subtraction of figures, as well as encouraged to memorize mottoes, verses, emblems, &c.

With the foregoing in view my present invention 20 contemplates the production of a series of playing-cards having novel features and elements of peculiar advantage in playing a variety of games, each one of which will not only afford recreation and amusement but will also be instructive and elevating 25 to the minds of the players.

The following specification embodies a full description of my invention, including 30 an explanation of certain games which may be played with the cards, and what I particularly claim as new is specifically set forth in the appended claims.

In the accompanying drawings: Figure 1 is a face view of a portion of a pack of cards, 35 to illustrate the general application of features constituting my present invention. Fig. 2 is a similar view showing an arrangement of the cards in counting points after playing one of the games hereinafter explained. Fig. 3 is a detail face view of a 40 portion of one of the cards composing a pack.

In carrying out my invention each playing-card is provided in one of its upper corners, preferably the left-hand corner, with a 45 numeral; and at the other, or right-hand corner, with a letter of the alphabet; and inasmuch as the cards may be reversed end for end the numeral is repeated in the diagonally opposite corner and the letter likewise 50 repeated in the other diagonally opposite corner—whereby when either end of the card becomes the top the relative arrangement of the numeral and letter will be the same. All 55 the letters of the alphabet are used on different cards, being duplicated according to the

number of cards in a pack, and the numeral associated with each letter is repeated on duplicates of that letter.

Referring to the cards shown in Fig. 1 of the drawings, the first or top card with the letter U has the numeral 1, the second with the letter V has the numeral 2, the third with the letter S has the numeral 8, and so on. Of course the association of the letters 60 and value of the accompanying numerals is arbitrary, but in the present instance each vowel is of the value 1, and the consonants increase in value from 2 to 9, in series. Any number of cards may be used in a pack, and 65 preferably the vowels are duplicated more often than the consonants, so that a greater number of words may be spelled with the 70 cards of a pack.

For the purpose of ornamentation each 75 letter and numeral is inclosed within a circle 10, and in addition to the capital letters in the diagonally opposite corners there are companion small letters, referred to by the reference-numeral 11, so that a child may 80 become acquainted with the different formation of each letter; and for the same reason Roman characters, as indicated at 12, are used in company with the numerals.

Each card is provided with suitable pleasing and instructive pictorial features, for instance a flag, 13, and in connection with the flag a suitable appropriate verse, as 14, is placed in the space at that end of the card having the flag. At the other end portion of 90 the card a different series of pictures may be employed; for instance birds, one of the cards showing an owl 15, with an appropriate verse 16. It will be understood, of course, that the flags, birds, and verses differ 95 on the several cards of a pack, for the sake of variety, and instead of having flags soldiers may be pictured, and animals in place of the birds; in other words, the matter printed on the cards may be changed, keeping in view the particular general features of the card herein shown and claimed.

The several cards in this instance represent different nations, according to the letter on the card—as, U the United States of 105 America; G Germany; S Switzerland; E England; and so on, and in connection with the several cards the flags of the respective nations are used, as well as the national anthem or other appropriate verse or verses. 110 The name of the nation is conspicuously placed at different sides of the center of the

card, at one side in capital letters and at the other in small letters or italics; and similarly the verse in the space at one end of the card is in capital letters and that in the space at the other end of the card in small letters or italics. As is usual with playing-cards the matter printed at one end portion is reversed from that printed at the other. In addition to the flags of the nations, &c., 10 suitable insignia, as a star 17, cross, etc., may be placed on the card.

Several different games may be played with a pack of cards having the novel features hereinbefore described; for example 1. the simple well-known game of "word-making and word-taking," in which the cards are dealt to the players and as they are played in succession any player may claim those exposed cards which spell a word of 20 more than three or four letters, according to agreement, the player depositing the last card of course having preference if he makes the claim at once. In this game when all the cards have been played and taken the 25 points are counted according to the numerals on the cards taken in by each player, and the players are thereby required to add the several numbers to get the total. Of course in playing this game with these cards each 30 player should be careful in making a word to play the consonants having the greatest value, and this of course adds to the interest in the game.

Another, and probably a more interesting 35 game, may be played by permitting a player to take exposed cards from the table either by making a word or when the numerals added together total a certain number, for instance 23. As an example, if the cards 40 G—6; R—7; W—4; and N—4 are exposed on the table and the one to play has B—2 in his hand he may put it down and claim the cards mentioned, as they total 23; or if he has also O—6 he may instead use this card 45 by making the word "grown," and of course in this instance he gets a greater number of points by making the word, inasmuch as O is of a greater value than 2 (B). In counting points in this game the player is allowed 50 to add together all the numerals on the cards he holds, and in addition increase the total by arranging his cards to spell the longest

word he can, in which case the first letter of the word adds one, the second two, the third three, and so on. As an example the 55 cards shown in Fig. 2 represent a total of 78 points—the numerals when added together giving 42, and the letters of the word "elephant" when added together as above described giving 36. Of course in summing up the total points the cards for convenience are arranged as shown in Fig. 2, the numerals of course all being in line, and the letters likewise in line. This game is very interesting and serves as a medium for teaching 60 orthography and the addition of figures. Of course as a diversion, and to teach the subtraction of figures, some of the cards may have numerals with the minus sign in front.

Other games may be played with the 70 cards, and it will be especially noted that the peculiar arrangement not only provides interest in the game but also includes features which will appeal to children. In addition to word-making and word-taking and 75 "totals" there may be played the game of "flags", and game of "nations", &c., providing a wide variety of games.

Having described my invention, I claim:

1. A pack of playing-cards each card of 80 which bears at one end thereof a numeral in one corner and a letter of the alphabet in the other corner, as herein shown and for the purpose set forth.

2. A pack of playing-cards each card of 85 which bears a numeral in a corner at one end thereof, a letter of the alphabet in the other corner of that end of the card, and corresponding numeral and letter in the corners at the other end of the card diagonally opposite the first mentioned numeral and letter, respectively. 90

3. A pack of playing-cards each card of which bears at one end thereof an Arabic numeral in one corner and a capital letter in 95 the other corner, together with small letters associated with the capital letter and corresponding Roman characters associated with the Arabic numeral, substantially as shown and for the purpose set forth.

URBAN S. ALSRUHE.
